US0D1076203S

(12) **United States Design Patent** (10) Patent No.: **US D1,076,203 S**
(45) Date of Patent: ** May 20, 2025

(54) **LAMP**

(71) Applicant: **MCM Global AG**, Zug (CH)

(72) Inventors: **Alberto Biagetti**, Milan (IT); **Laura Baldassari**, Milan (IT)

(73) Assignee: **MCM GLOBAL AG**, Zug (CH)

(**) Term: **15 Years**

(21) Appl. No.: **35/520,696**

(22) Filed: **Apr. 11, 2024**

(80) **Hague Agreement Data**

Int. Filing Date: **Apr. 11, 2024**

Int. Reg. No.: **DM/236641**

Int. Reg. Date: **Apr. 11, 2024**

Int. Reg. Pub. Date: **May 3, 2024**

(51) **LOC (15) Cl.** **26-05**

(52) **U.S. Cl.**

USPC **D26/110**; D26/93

(58) **Field of Classification Search**
